UNITED STATES PATENT OFFICE

SUSAN J. HAIGNEY, OF BROOKLYN, NEW YORK

PACKAGE OR CONTAINER FOR LIQUIDS

Application filed October 5, 1926. Serial No. 139,598.

This invention relates to packages or containers, and more particularly to containers for liquid, and has as an object to provide a container which shall prevent leakage of the liquid contents when the container is closed, but which shall provide a convenient means for applying the liquid contents when the container is opened.

Other objects and advantages of the invention will appear hereinafter.

A preferred embodiment of the invention selected for purposes of illustration is shown in the accompanying drawings, in which,

Figure 1 is a side elevation.

Figure 2 is a section on the line 2—2 of Figure 1.

Figure 3 is a side elevation of the fluid container.

Referring to the drawings, the package comprises an outer casing 1 and an inner liquid container 2. The outer casing which may be of wood or metal may be conveniently divided into two sections 3 and 4

which may be secured together either frictionally or by means of the screw thread 5.

The top section 3 of the casing may be provided with a cavity 6 into which is fitted a cap 7 of rubber or other suitable material which in turn is provided with a cavity 8 which is adapted to receive the reduced end portion 9 of the liquid container 2. Preferably the reduced end portion may be corrugated or threaded in the manner illustrated in order to provide a reasonably tight

frictional engagement between the surface of the reduced end portion and the surface of the cavity 8. Such engagement is desirable for two reasons, first, to prevent leakage of the liquid contents from the container 2 and, second, to hold the container 2 to the top section 3 without the provision of any other supporting means.

As will be observed, the bottom section 4 of the casing merely surrounds the liquid container to prevent damage thereto, but does not serve to support the liquid container.

The reduced end portion 9 of the liquid container is provided with a relatively small duct 10 through which the liquid contents may be ejected from the container, but pref-

erably this passage is of a size to prevent the escape of liquid except as desired by the user. As will be understood, liquid may be ejected by shaking the container, or in cases where it is desired to use the end portion 9 as an applicator, surface tension may be sufficient to cause the desired flow of liquid through the passage 10.

Preferably, however, means are provided by which the liquid may be ejected from the container, such means being illustrated in the preferred embodiment as comprising a flexible cap 11 of rubber or other suitable material which is mounted over the open end 12 of the container. In many cases it has been found desirable to line the interior of the rubber cap with a sheet 13 of collodion for example, for many of the liquids which the package is adapted to contain have a deleterious effect on rubber. As will be observed by pressing on the rubber cap, the contained liquid may be ejected as desired.

The described package may be conveniently carried by the user in a pocket or in a hand-bag for example, without danger of leakage of the liquid contents and without danger of breakage, due to the resilient manner in which the liquid container is supported in the rubber cap 7. If desired, the liquid container may be used as an applicator or by pressing on the rubber cap 11 may be used as a dropper. When the reduced end portion of the liquid container is inserted in the rubber cap the container is tightly sealed and at the same time the rubber cap provides a resilient support which serves to protect the liquid container from damage due to shock, as for example, if the package is dropped. Furthermore, even when removed from the outer casing, the liquid container may be laid on its side or may be held in upright position without leakage.

It will be understood that the invention may be variously modified and embodied within the scope of the subjoined claims.

I claim as my invention:

1. A package for liquids, comprising, a liquid container having a duct in one end, an outside casing for said container having a

cap, and resilient means having a cavity therein mounted in said cap, the cavity in the resilient means closely and removably engaging the duct end of said liquid container to resiliently support said liquid container within said casing and seal said duct.

2. A package for liquids, comprising, a liquid container having a reduced end portion having a duct therein, an outside casing for said container having a cap, and resilient means having a cavity therein mounted in said cap, the cavity in the resilient means closely and removably engaging the reduced end portion of said liquid container to resiliently support said liquid container by said reduced end portion within said casing and seal said duct.

3. A package for liquids, comprising, a liquid container having a reduced end portion having a duct therein, said container being provided with a diaphragm forming a flexible wall thereof, and an outside casing having means to seal said duct and to support said container and to protect said flexible wall against pressure.

4. A package for liquids, comprising, a liquid container having a reduced end portion having a duct therein, and an outside casing carrying a cap at least in part of resilient material having a cavity into which said reduced end portion fits snugly whereby said container is sealed and supported.

5. A package for liquid comprising, a liquid container having a screwthreaded, reduced end portion having a duct therein, and an outside casing having a cap with a cavity therein to receive the screwthreaded, reduced end portion of the container to seal said duct and resiliently support said container.

40. 6. A package for liquid, comprising, a liquid container having a reduced end portion having a duct therein, said container being provided with a diaphragm forming a flexible wall thereof, and an outside casing having a cap with a cavity therein to receive the reduced end portion of said container to seal said duct and resiliently support said container.

In testimony whereof, I have signed my name to this specification this 1st day of October, 1926.

SUSAN J. HAIGNEY.
